SURFACE DRAIN CULVERT

George W. Sondag, Oakland, Calif., assignor to
The American Rolling Mill Co., Middletown,
Ohio, a corporation of Ohio

Application January 8, 1935, Serial No. 839

5 Claims. (Cl. 94—33)

The present invention relates to an open culvert for draining the surface of a roadway and for other similar uses.

In constructing roads, especially those having 5 a gravel or dirt surface upon grades, it is customary to provide ditches or water breaks across the surface of the road to carry off to one side the rainwater which runs longitudinally down the road, which if allowed to continue for any 10 great distance will wash away the surface material, especially if the surface is worn into wheel ruts in which the drainage concentrates.

The principal object of the present invention is to provide a culvert of trough like form 15 which can be embedded in the surface material of the road and which will effectively carry off the surface drainage therefrom.

Other objects of the invention are to provide a culvert of the described type which is inexpensive to construct and install, which is easy 20 to maintain in proper operating condition, which will have long life, and which will not present any obstruction or unevenness in the surface of the road to interfere with the passage of traffic 25 over it. Although the device is herein illustrated and described as used for draining a roadway, it is to be understood that it may also be used without change of form for draining any flat surface. It is also to be understood that changes, 30 within the scope of the claims hereto appended, may be made in the form, construction and arrangement of the device without departing from the spirit of the invention as defined in said claims.

35 Reference will be made to the accompanying drawing in which

Fig. 1 is a plan view of a roadway showing the culvert installed therein.

Fig. 2 is an enlarged section on the line 2—2 40 of Fig. 1.

In the drawing, the reference numeral 3 designates the surface of a roadway, which may be composed of any suitable material, as for example gravel or dirt. In Fig. 1 of the drawing 45 the road surface 3 is to be understood as sloping upwardly toward the right, so that any water falling or lying upon the surface will run longitudinally from right to left.

The culvert embodying the present invention 50 in its preferred form consists of a strip of metal, preferably steel, which is bent longitudinally into the form shown in Fig. 2 with a central depressed trough 4 of substantially V-shape with a rounded bottom 5. The central trough 4 is 55 bordered by inverted V-shaped portions 6 with

rounded tops 7, and the edge portions of the strip are bent horizontally outwardly as at 8 and preferably turn up slightly at their extreme edges, as shown at 9. The approximate shape of the entire culvert is that of an inverted W. 5

The culvert is embedded in the surface material as shown, with its rounded upper bends 7 approximately flush with the surface of the road. This is accomplished by digging a ditch across the road the full width of the culvert, 10 laying it in place in said ditch, and back filling the road material over the side flanges 8. For best results, the road material should fill the spaces beneath the upper bends 7, especially at the upper end of the culvert to prevent water 15 from entering under said upper bends and washing out the material beneath the culvert.

On grades, the culvert is installed at an angle to the transverse line of the road, as illustrated in Fig. 1, so that one end is higher than the 20 other end. The slope or grade of the culvert itself should be approximately eight per cent, and where the road is cut into a bank, as on a side hill, the upper end of the culvert should be at the inside or bank of the road. The outer 25 or lower end of the culvert preferably extends out slightly beyond the edge of the roadway, as shown at 10 in Fig. 1, and suitable provision, not shown, should be made for carrying off the water from said lower end to prevent washing 30 the outer bank of the road. Thus the water which flows longitudinally down the road drains into the trough 4 of the culvert and is carried off laterally. The culverts are placed at sufficiently close intervals, depending upon the grade 35 of the road and the character of its surface material, so as to prevent the accumulation of sufficient longitudinal drainage to cause erosion of the surface.

The trough 4 of the culvert is so small as to 40 cause no interference to traffic. In practice, the distance from center to center of the upper bends 7 is approximately five inches. The rounded form of said upper bends provides smooth edges for the trough and the rounded bottom 45 5 enables it to be easily cleaned out. If desired, in locations where long dry seasons exist, the trough 4 may be filled up with road material during the dry season, and can be easily and quickly cleaned out at the beginning of the rainy 50 season.

The culvert is made of sufficiently heavy material, in practice about one eighth of an inch thick, to prevent it from being bent by the passage of vehicles over it, and if desired it may be galvanized 55

to prevent rusting. The side flanges 8 with their turned up edges 9 provide firm anchors for the culvert, so that when once installed it is not shifted or even loosened by the passage of traffic, 5 as long as the road material is kept up to approximately the level of the upper bends 7.

I claim:

1. A surface drain culvert comprising a strip of metal having a longitudinal central trough, the 10 sides of said trough flaring outwardly and upwardly and thence into a rounded curve and downwardly and outwardly to form anchoring flanges adapted to be embedded in the ground, whereby to form rounded wearing edges, which 15 are substantially flush with the ground surface at its junction with the trough when said culvert is emplaced, the lowest portion of said flanges being approximately at the level of the bottom of said trough.
2. A surface drain culvert comprising a strip of metal having a longitudinal central trough, the 20 sides of said trough sloping outwardly and upwardly, thence turning in a rounded curve to an outward and downward slope, and finally extending approximately horizontally outwardly, the 25 downwardly sloping and horizontal portions forming anchoring flanges, and the rounded curves adapted, when said culvert is in position in a road surface, to form broad wearing edges at the junction of the trough with the ground surface.
3. In combination with a road surface, a sheet 30

metal drain culvert embedded in the road material and comprising a substantially rigid trough member inclined longitudinally at an angle to the horizontal to carry away surface water and having its side walls flaring upwardly and outwardly each 5 merging into a broadly rounded curved wall disposed substantially tangential to the road surface, the outer portions of said curved walls extending downwardly and terminating in anchoring flanges embedded in the road material, the relatively broad space within and beneath said curved walls being filled with road material to reinforce the culvert to resist distortion and collapse due to the wear and weight of traffic.

4. In combination with a road surface, a drain 15 culvert embedded in the road material comprising a sheet metal member of substantially inverted W cross-section, having rounded apexes 10 disposed substantially tangentially to the road surface, the outer walls terminating downwardly 20 in outwardly extending anchoring flanges.

5. In combination with a road surface, a drain 25 culvert embedded in the road material comprising a sheet metal member of substantially inverted W cross-section, having rounded apexes 25 disposed substantially tangentially to the road surface, the outer walls terminating downwardly 30 in outwardly extending anchoring flanges, the spaces under said apexes being filled with the road material for additional support.

GEORGE W. SONDAG.
